MACHINE FOR COMPRESSION OF FLUIDS

Arthur C. Layton, Tyler, Tex.

Application July 3, 1951, Serial No. 235,040

12 Claims. (Cl. 230—108)

1

My invention consists of a machine for the compression of gases, vapors, and liquids. It is especially designed for use as a refrigeration compressor in a system consisting of a compressor, condenser, receiver, and evaporator.

In the operation of a refrigeration system of this type, a quantity of liquid refrigerant such as sulphur dioxide, methyl chloride, or Freon is placed in the receiver. The refrigerant will then assume a pressure corresponding to its boiling point at the temperature of the receiver and environs. Liquid refrigerant from the receiver, under pressure, is admitted to the evaporator where it is vaporized through absorption of heat from the environs of the evaporator. The compressor is used to remove from the evaporator this vaporized refrigerant. The vapor, at relatively low pressure, is compressed to a higher pressure and, therefore, assumes a higher temperature corresponding to the new pressure conditions. Heat of the vapor is removed in the condenser, where the cooled refrigerant reverts to the liquid state and flows into the receiver to complete the cycle. From the above, it will be observed that the function of the compressor is to create an unbalanced pressure condition in the refrigeration system. Ideally, only gas vapor is handled by the compressor. However, oil from the compressor is always present with the refrigerant; also, liquid refrigerant boils over from the evaporator and causes failure and breakage of the compressor. These are some of the defects which are present in the art at this time and which are reduced or eliminated by my invention.

Another defect in conventional compressors is that during extremely hot weather the condensing pressures are so high that motors fail due to excessive head pressure. Elimination of this difficulty is another object of this invention.

Still another object is elimination of the compressor valves which are employed in conventional compressors and which are rendered inoperative by minute particles of foreign substance holding the valves open, by breakage of the valves due to slugs of oil or liquid refrigerant and by other mechanical failures.

A further object is the elimination of the cranks and pistons which are employed in conventional compressors and which sometimes seize the cylinder walls due to the presence of foreign substances.

An important object of this invention is the elimination of outside seals which leak and cause loss of refrigerant from the system, or admit air and moisture to the system. In either case the

2

system is rendered inoperative due to leakage of the seal.

Another important object is the reduction of wear to a minimum by elimination of unbalanced mechanical forces which are usually applied to moving parts.

Still another important object is the elimination of the necessity for high torque, slow speed motors. These are usually required due to starting off under heavy load. Simple, high speed motors which are more economical in first cost and operating cost can be substituted for the former.

A preferred form of the invention is shown on the attached drawings in which:

Figure 1 shows a vertical section taken along the central axis of my machine;

Figure 2 is a horizontal cross-sectional view in which the upper right hand quadrant shows a section taken along the line A—A in Figure 1; the upper left hand quadrant shows a section taken along the line B—B of Figure 1; the lower left hand quadrant shows a section taken along the line C—C Figure 1; and the lower right hand quadrant shows a section taken along the line D—D, Figure 1;

Figure 3 shows the vertical pipe assembly removed from the machine; and

Figure 4 is a fragmentary vertical cross-section showing a modified construction 3 at the base of the compressor.

The invention consists of a compressor body 11, comprising upper and lower halves, the two halves being fastened together to form a hermetically sealed vessel. Communicating pipes 12, herein referred to as the suction pipe, and 13, herein referred to as the discharge or hot gas line are secured to the body 11, and connect to the evaporator and condenser respectively. The lower half of the body 11 is formed with a pocket or sump 14 disposed axially and projecting upwardly from the lowest section of the interior of the body 11. The sump 14 has a plurality of radially disposed ports 15 communicating with the interior of the body 11.

A vertical pipe 16 is disposed coaxially of the body 11, communicates at its upper end with the suction pipe 12, and is connected at its lower end to the sump 14 by means of a central opening 37 in the top of the sump 14. This pipe 16 is formed with a partition 17 located at its approximate mid-section which divides the pipe into an upper chamber 18 and lower chamber 19. The upper end of the pipe 16 is secured by means of a locking nut 20 fitted into an annular recess near the

top of the body 11. The connection between the body 11 and the pipe 16 is hermetically sealed by means of the gasket 21 disposed axially between the nut 20 and the body 11. The pipe 16 is formed with a horizontal exterior groove encircling it at the portion containing the partition 17, midway between the chambers 18 and 19, forming a space 23 around the circumference of the pipe 16. A plurality of radially disposed ports 22 lead from the extreme lower end of the chamber 18 to the space 23, and a corresponding group of radially disposed ports lead from the extreme upper section of the chamber 19 to the space 23 and are designed to receive the nozzles 24.

A check valve 25, consisting of upper and lower guides 57 and 58 respectively; and a movable disc 59 formed on a rod 60 inserted between the upper and lower guides and biased upwardly by a spring 53 is located at the extreme upper end of the chamber 18 in an enlarged section of the pipe 16. The upper guide 57 of the check valve 25 forms locking means for securing the check valve in position. A gasket 26 between the upper guide and the shoulder formed in the pipe 16 hermetically seals the chamber 18 when the check valve is in the closed position.

An elongated sleeve 27 surrounds the upper section of the pipe 16, forms a bearing surface with it, and is free to rotate about it. Upward axial movement of the sleeve 27 is prevented by a shoulder 28 formed in the upper section of the body 11. The lower end of the sleeve 27 projects downwardly, incloses a portion of the space 23 formed by the groove in the pipe 16, and carries a radially extended flange 29. This flange 29 is securely fastened to and supports a disc 30, which therefore rotates with the sleeve 27.

Another sleeve 31, formed substantially the same as the sleeve 27 except that its flanged portion is located at its upper end, encircles the lower part of the pipe 16. The flanged end of the sleeve 31 extends upwardly to the space 23, and is securely fastened to the disc 32, the sleeve and disc being free to rotate about the pipe 16. The discs 30 and 32 are disposed radially of the pipe 16 adjacent to the space 23, and are axially opposed. Axial movement downwardly of the sleeve 31 is prevented by the shoulder 40 formed in the top of the sump 14 surrounding the central opening 37 which secures the pipe 16.

A plurality of curved elements 33 are regularly spaced between the discs 30 and 32, said elements extending radially, and curving tangentially, to the periphery of the discs 30 and 32, the elements being secured between, and to, the discs by any convenient means, and forming therewith a plurality of elongated ports 34 constituting communicating means between the space 23 and the interior of the body 11. The assembly, consisting of the sleeves 27 and 31, the discs 30 and 32, and the elements 33, is thus free to rotate as a unit about the pipe 16, the pipe forming a bearing surface and supporting means for the assembly.

The armature, or rotor 35 of an electric motor, is formed as a ring secured to the sleeve 27 and disposed concentrically therewith and is located axially between the flange 29 and the shoulder 28, the rotor thus forming a part of the assembly as outlined above.

A tube 36 disposed axially of the chamber 18 projects downwardly through the port 38 formed in the partition 17 and extends upwardly into the chamber 18 to a point just below the check valve, at which point the tube 36 makes a right angle

turn and enters a port 50 in the wall of the pipe 16, thereby forming a communicating passage between the chamber 19 and a horizontal annular groove 51 in the exterior surface of the pipe. The connection between the tube 36 and the port 38, also the connection between the tube 36 and the port 50 are hermetically sealed from the chamber 18.

Another port 39 in the wall of the pipe 16 is located at the lower end of the pipe 16 just above the lower end of the sleeve 31. This port leads to an annular groove 52 formed horizontally on the outer surface of the pipe 16, and constitutes a communicating passage between the chamber 19 and the groove 52.

A diverter ring 41 carrying an outer flange 42 encircles the discs 30 and 32. Immediately therebelow a guide ring 44 in the shape of a centerless bowl carries a corresponding outer flange 45 which registers with flange 42 of the ring 41. The body 11 is formed in upper and lower halves and the interior sides of the mating edges of these halves are cut back to define a horizontal annular groove in which the flanges 42 and 45 are clamped between the upper and lower halves of the body 11. Ports 43 in the flange 42 register with ports 46 in the flange 45 and constitute a passageway between the upper and lower halves of the chamber enclosed by the body 11.

A plurality of cylindrical perforated sleeves 48 of varying diameter, disposed axially and spaced radially, are suspended from the guide ring 44 and project downwardly to the bottom wall of the body 11. The lower edges of the sleeves 48 are designed to permit liquid to flow along the bottom wall of the body 11 to the ports 15 in the sump 14.

An elongated sleeve 49 formed with a flared upper end encircles the sleeve 31 and the shoulder 40 of the sump 14, the sleeve 49 being secured by any convenient means to the outer wall of the sump 14 above the ports 15. A port 47 is formed radially in the sleeve 49, the port 47 being located at any convenient point near the lower end of the sleeve 31, and forming communicating means between the lower end of the space between the sleeves 31 and 49 and the interior of the body 11.

A frusto-conical dispersion plate 54 is affixed to and supported by the midsection of the sleeve 49, the plate extending radially therefrom and sloping downwardly to the inner cylindrical surface of the nearest perforated sleeve 48.

A sleeve 55 containing the field or stator of an electric motor is affixed to the interior of the upper half of the body 11 and encircles the rotor 35 affixed to the sleeve 27.

A terminal plug 56 is located at any convenient point in the wall of the body 11, and serves to form sealing and insulating means for inserting electric wires for connection to the electric motor. The plug 56 is of standard manufacture and is not claimed as a part of this invention.

The various parts are preferably formed of metal suited to the design and application. While a particular preferred embodiment of the invention has been described, it will be apparent to those skilled in the art that various changes and modifications may be made without departing from the invention.

In operation (after first making suitable connections with the evaporator, condenser and receiver, which complete a hermetically closed refrigeration system), the vapor compression machine, hereinafter referred to as the compressor, is evacuated of all moisture and non-

condensable air or gases. After the system is completely evacuated, the sump 14 and the lower portion of the body 11 is filled to the approximate height of the lower edge of the dispersion plate 54, with a dehydrated lubricating oil suitable for the purpose.

Refrigerant is now added to the system in the desired quantity, and pressures throughout the system reach a state of equilibrium in all parts of the system, including the compressor. Liquid refrigerant is added at the receiver—the remaining parts of the system contain only refrigerant vapor at the beginning—the vapor condensing to a liquid under suitable temperature and pressure conditions. The check valve 25 remains closed as long as the pressure on the upper and lower side is balanced, the spring under the check valve forcing the check valve upwardly against the seat, the spring being just strong enough to overcome the weight of the valve.

The motor is then started by external starting means. The discs 30 and 32 bearing the curved elements 33 will assume the speed of the rotor 35, as they are fixed to the sleeves 27 and 31 to form an assembly which constitutes the only rotating, or movable, part of this invention, aside from the check valve. As heretofore pointed out the invention contemplates the use of high-speed electric motors, and the ports 34 contain dense refrigerant vapor at the pressure and temperature of the refrigerant vapor in the body 11 and the remainder of the refrigeration system. However, the vapor contained in the rotating ports 34 is biased outwardly by centrifugal force as the assembly is rotated, this force being a function of the weight per unit volume of the vapor, and the peripheral speed of the rotating discs 30 and 32. Any vapor ejected from the ports 34 will cause a reduction of pressure in the space 23 and consequently in the chamber 19 with which that space communicates through the ports 22. The pressure in the chamber 19 will also be reduced by means of the nozzles 24. As rotation continues a constantly increasing pressure differential will be built up between the vapor in the body 11 and the vapor contained in the space 23, the chamber 18, and the chamber 19. This pressure differential will cause a downward pressure upon the oil in the lower portion of the body 11, forcing the oil into the chamber 19 by means of the ports 15 and the sump 14. This action will in turn produce a rise in the oil level of the chamber 19 to correspond with the pressure differential previously described. When the oil in the chamber 19 has completely filled the chamber, a further pressure differential will cause oil to flow from the nozzles 24, where it is picked up by the rapidly rotating elements 33 and directed into the ports 34. Now, since the density of the oil is greater than the refrigerant vapor residing in the ports 34 the centrifugal effect on the oil will be correspondingly greater, thus causing drops of oil to be ejected outwardly from the ports 34 which will force vapor from the ports 34 and produce a still greater pressure differential between the vapor in the body 11 and the vapor in the chamber 18. This action will in turn produce a greater flow of oil from the nozzles 24. From the above description it will be observed that slugs of oil injected into the rotating ports 34 by the stationary nozzles 24 serve as movable pistons to eject refrigerant vapor from the ports 34 into the pressure vessel comprising the interior of the body 11. The slugs of oil ejected from the

ports 34 with the vapor, are thrown tangentially against the sloping wall of the diverter ring 41 where the impact is small due to the angle of approach. The oil is thus spread thinly by the force of the impact and its velocity dissipated in a swirling motion about the wall of the guide ring 44. The oil then flows by gravitational effect down the sloping wall of the guide ring 44 and falls to the dispersion plate 54 and settles to the bottom wall of the body 11 to be re-cycled as before.

When the pressure in the system above the check valve exceeds the pressure in the chamber 18, the spring pressure will be overcome by the pressure difference and permit refrigerant vapor to flow into the chamber 18, through the ports 22, into the space 23, and into the rotating ports 34 where it is ejected into the body 11 and out through the outlet 13 to the condenser, (not shown). Additional vapor ejected into the body 11 from the rotating ports 34 will produce a higher pressure in the body 11 and a greater pressure differential between the body 11 and the space 23. It is highly important that the amount of oil delivered by the nozzles 24 be limited by the design of the nozzles 24 to obtain the desired operating pressure differential in the system.

In the description thus far the oil and refrigerant vapor have been considered as separate entities. Actually, the oil will absorb large quantities of refrigerant in either the vapor or liquid state. The amount of refrigerant absorbed by the oil will vary directly with the pressure and inversely as the temperature. Advantage is taken of this property as follows: The oil contained in the body 11 is under relatively high pressure and contains a large amount of refrigerant. When refrigerant bearing oil is ejected from the nozzles 24 it experiences a sudden reduction of pressure, whereupon the refrigerant will expand and break the oil up into a foam, the foam occupying a larger volume than the oil; consequently the rotating ports 34 will contain slugs of expanding foam which will more effectively force the vapor ahead of the slugs of foam. Oil foam and vapor thrown tangentially against the diverter ring 41 will drive the vapor from the oil by the force of the impact. It is to be observed that the original quantity of vapor contained in the oil will be re-absorbed since the pressure-temperature conditions have been restored. Oil and vapor are directed through the perforated sleeves 48, the oil settling to the bottom of the vessel, while the vapor containing particles of oil pass through the remainder of the sleeves 48, the oil particles being deposited on the sleeves 48 and settling to the bottom of the vessel, while the vapor continues upwardly through the ports 43 and 46 respectively, to the upper section of the body 11 and through the outlet 13 to the condenser (not shown). It is pointed out that oil is always present with the refrigerant in conventional refrigeration systems. While the oil has no refrigerating property it acts as a very effective retardant to heat transfer in the evaporator and causes a loss in efficiency of the system. This defect is reduced or eliminated by my invention, by removal of oil from the vapor while still in the compressor, as outlined above.

While a pressure difference exists between the lower end of the sleeve 31 and the space 23, oil will leak into the space forming the bearing surface between the pipe 16 and the sleeve 31. This leakage will be relatively small and will serve to

form a liquid seal to reduce leakage and will also serve to lubricate the bearing between the pipe 16 and the sleeve 31, and the bearing between the sleeve 31 and the shoulder 40 which supports the rotating assembly. The grooves 52 and 54 are provided externally of the pipe 16 to facilitate this lubrication. The groove 52 is supplied with oil under pressure by means of the port 39, while the groove 54 is supplied with oil under pressure by means of the port 38, the tube 36, and the port 50. The sleeve 49 is provided to prevent oil from contacting the exterior of the sleeve 31. It is pointed out that the sleeve 31 in rotating would cause a swirling of oil which could permit a complete loss of oil from the ports 15 and permit vapor to enter the chamber 19 from the ports 15. Contact of oil with the exterior of the sleeve 31 would also produce a skin friction between the sleeve 31 and the oil. The small port 47 formed in the wall of the sleeve 49 serves to drain oil from the space about the sleeve 31.

One of the advantages of this invention over conventional compressors is due to the intimate relation between the vapor under compression in the ports 34 and the oil producing the compression. It is pointed out that in conventional compressors containing valves, the vapor must be compressed to a higher pressure than exists in the system due to inertia of the valves which must be overcome before the compressed vapor can be discharged into the system. After the valves are opened by the pressure difference, a re-expansion takes place into the system which does no useful work. Also to be observed is the fact that compression to a higher pressure than exists in the system will produce a higher temperature in the compressor. Both of these defects are reduced or eliminated in my invention. Another advantage is due to the heat absorbed by the oil during compression and dissipated by the compressor thus reducing some of the work of the condenser. Since the lower temperature of the oil will effect a lowering of the compression pressure and temperature, an increase in efficiency may be obtained by cooling the oil in the compressor by external means. This may be effected by the simple method illustrated in Figure 4 without departing from this invention. As shown in this figure, the ports 15 communicating with the sump 14 are closed off. An auxiliary port 61 is formed in the sump 14 to serve as an inlet from the exterior of the body 11. Another port 62 in the bottom wall of the body 11 adjacent to the sump 14 forms an outlet from the bottom of the body 11 so that oil may be directed through an auxiliary circuit in the condenser by means of the second port and returned to the first port formed in the sump. Pressure differential between the body 11 and the chamber 19 will produce a circulation of the oil as before and effect an increase in the efficiency of the system. A further increase of efficiency may be effected by proper design of the nozzles 24 to give a maximum spouting velocity to the oil.

This invention may be used for a steam condenser evacuation pump by substituting water for the oil. It may also be used for the compression of air and other gases by substituting a suitable liquid.

What I claim is:

1. A fluid compressor comprising a vertical cylindrical pressure vessel having separate upper and lower inner chambers formed coaxially within said pressure vessel so that the balance of the vessel constitutes an outer chamber encircling

said inner chambers, an outlet from said outer chamber to and an inlet to said upper chamber from without the vessel, at least one communicating channel between the outer chamber and the lower end of said lower inner chamber, adjacent radial passageways from the upper end of said lower chamber and from the lower end of said upper chamber to said outer chamber, outwardly pointing nozzles in said first-named passageways, a sleeve rotatable about said inner chambers, said sleeve being divided into upper and lower sections, two axially opposed horizontal discs fixed to said sleeve between said sections, a plurality of arcuate spacers separating said discs and forming therewith a plurality of radial ducts in horizontal alignment with said radial passageways, said ducts curving continuously away from a line radial of said discs toward their perimeter, and means for rotating said sleeve about said chambers.

2. A compressor as claimed in claim 1 in which said inner chambers are formed by a cylindrical wall extending coaxially within said vessel and said wall serves as a bearing surface for said rotatable sleeve.

3. A compressor as claimed in claim 2 having cylindrical projections from the upper and lower walls of said vessel which serve as bearing surfaces for said sleeve.

4. A compressor as claimed in claim 3 in which oil is carried in said lower inner chamber and the bearing surfaces formed for the rotating sleeve by the walls of the inner chamber are provided with special passages for the admission of oil passing from said lower chamber to said bearing surfaces for the lubrication thereof.

5. A compressor as claimed in claim 1 in which said vessel is formed of upper and lower sections secured together and has an interior annular groove where the sections meet, and in which a frusto-conical ring has a radially disposed outer flange clamped in said groove, said ring projecting inwardly above said ducts and said flange having a plurality of circumferentially spaced ports therein.

6. A compressor as claimed in claim 1 in which said vessel is formed of upper and lower sections secured together and has an interior annular groove where the sections meet, and in which a ring formed as a centerless bowl has an outer radial flange mounted in said groove, said flange having a plurality of circumferentially spaced ports and said ring projecting inwardly of said vessel, below said ducts.

7. A compressor as claimed in claim 6 in which a frusto-conical ring carries an outer flange clamped into said groove, said frusto-conical ring extends inwardly of said vessel above said ducts and the flanges of both of said rings carry registering circumferentially spaced ports.

8. A compressor as claimed in claim 7 having a plurality of spaced perforated sleeves extending upwardly from the bottom of the outer chamber and concentrically disposed about the lower inner chamber.

9. A compressor as claimed in claim 8 in which a solid cylindrical sleeve projects upwardly about the lower half of said rotating sleeve and carries at its approximate mid-point a frusto-conical ring projecting outward and downward to the innermost of the perforated sleeves.

10. A compressor as claimed in claim 1 in which the channel between said outer chamber and the lower end of the inner chamber passes through a cooler.

11. A compressor as claimed in claim 1 in which a pressure responsive valve at the entrance to said chamber controls the flow of fluid in the inlet to said upper chamber.

12. In combination, a compressor as claimed in claim 1 and an electric motor for rotating said compressor, said motor comprising a rotor fixed to the upper portion of said rotating sleeve and a stator fixed to the interior of the upper part of the outer wall of said outer chamber.
